UNITED STATES PATENT OFFICE.

TIMOTHY CARROLL, OF ANAHEIM, CALIFORNIA.

HOPPER.

972,678.

Specification of Letters Patent. Patented Oct. 11, 1910.

Application filed May 1, 1906. Serial No. 314,683.

To all whom it may concern:

Be it known that I, TIMOTHY CARROLL, a citizen of the United States, residing at Anaheim, in the county of Orange and State 5 of California, have invented a new and useful Hopper, of which the following is a specification.

This invention has relation more particularly to that class of hoppers designed for 10 use in connection with crematories or other apparatus for the incineration of waste material, rubbish, garbage, etc.

One of the objects of this invention is to 15 produce a practical hopper which is so constructed that the escape of the injurious fumes, smoke, and heat is prevented when the material to be burned or destroyed has 20 been dumped into the crematory, and which can be safely and readily manipulated by the attendant to admit the material to be burned.

An object of the invention is to provide 25 a novel hopper adapted to be dumped into from wagons or carts on either side thereof, or on both sides thereof, provision being made whereby the attendant may dump into either of two or more openings from either side of the hopper, or can dump a part of the load into one side of the hopper and another 30 part of the load into the other side of the hopper without moving the vehicle from which the dumping takes place. In this connection an open hopper is provided having in its bottom a plurality of openings; and a plurality of covers are centrally 35 hinged, each adapted to swing over one of said openings and rest upon the rim of the hopper, or to swing over backward to rest on the other cover, or to be held upright 40 midway of the hopper.

Other features and advantages of the invention may appear from the subjoined detailed description.

It is one of the main objects of this invention 45 to produce a hopper which may be operated by any inexperienced hand, and furthermore, to combine means whereby the openings in said hopper to the crematory may be respectively opened and closed alternately or simultaneously.

It is to be understood that this invention 55 relates to crematories in which intense fire is maintained for the rapid combustion of materials difficult to consume, and that in consequence great danger has heretofore existed in the operation of such crematories

resulting in the loss of human lives and also of the teams employed for hauling the garbage to the crematories.

An object of this invention is to provide 60 means whereby the work of dumping the garbage into the crematory may be accomplished without any danger whatever to the operator, driver or team. This advantage is secured by peculiar arrangement of openings 65 into the top of the crematories and covers for such openings, and also the provision, construction and arrangement of means whereby the covers may be operated without any danger to operators, drivers or 70 other persons connected with the work.

The accompanying drawings illustrate the device in which—

Figure 1 is a top plan view of my improved hopper; Fig. 2 a vertical longitudinal section; Fig. 3 a side elevation showing the means for raising and lowering the covers, Fig. 4 a longitudinal vertical section of a modified form, and Fig. 5 a top view of Fig. 4 on a reduced scale. Fig. 6 is a top 75 view of a hopper having the same general form as that illustrated by Fig. 1, a single opening instead of a plurality of openings 80 being shown on each side of the division wall.

The upper portion 1 of a crematory is provided with a cap-plate 2" having a plurality of hopper-openings 2, and it is the object of my hopper to provide means for discharging material into the crematory 90 through these openings. The hopper is rectangular in plan and has vertical outer frame walls 3 and inclined inner hopper-walls 4, said hopper-walls leading to the openings 2. End walls *a* connect the ends 95 of the hopper walls 4. An A-shaped division wall 5 connects the end walls *a* to divide the hopper into two equal parts, said division wall leading to the inner side of the openings 2 in opposition to the walls 4. 100

In the construction shown in Fig. 1 there are two openings 2 on each side of the division wall 5, and a partition *b* having reversely-sloping walls separates these openings transversely of the wall 5. The height 105 of the division wall 5 is about one-third of that of the walls 3 or 4. Two division covers 6 are hinged to the top of the division wall 5, said division covers being adapted to swing to an inclined position and rest 110 upon the upper edges of the walls 3 and 4; said division covers being operated by means

of a chain 7 running over a pulley, said pulley being centrally suspended from the cross-beam 8 supported by the standards 9 which are mounted on the ends of the hopper. The several walls of the hopper arranged as described provide four openings 10 in the bottom of the hopper registering with the openings 2 in the cap-plate 2' of the crematory. Supplemental covers 11 are hinged to the inner faces of the hopper-walls 4 near their lower edges, said supplemental covers being adapted to swing downwardly to horizontal positions against the division wall 5, and said supplemental covers being operated by chains 12 connected to spools 13 fixed upon shafts 14 mounted upon the frame walls 3 and operable by cranks. Clutches 15 are provided upon the shafts 14, one clutch for each spool, so that by operating the clutches the supplemental covers may be operated independently or simultaneously. To further close the openings 2 and insure the retention of the fumes and heat in the crematory, slides 16 are provided on top of the cap of the crematory and below the hopper, said slides preferably operating crosswise of the hopper and each slide controlling two of the openings 2.

It will be seen from the drawing represented in Fig. 1 that a double hopper can be formed out of this arrangement by simply operating the chain 7 and thereby holding the respective division covers 6 upright in a position parallel with the side walls, and that a single hopper may be formed by throwing both of said division covers over to one side and in this case only one side of the hopper would be open for the reception of material.

40 In the modification shown in Fig. 4, three openings are thus shown in the bottom of the body portion extending the full width or length of the hopper. These openings are shown at 17, 18, and 19 in a row. To close said openings, supplemental covers 20 are provided in the bottom of the hopper, said supplemental covers 20 being operable by means of a chain and spool arranged on the side of the hopper-body. Division covers 21 are provided to lap over the supplemental covers 20, these covers being operable by a chain and pulley in like manner as in Fig. 1. Thus I provide three distinct independently-operated closures for each opening into the crematory. This arrangement of covers and hopper provides for three separate openings through the cap to the crematory, each of which is independent of the other and two of which may be used at one and the same time. All three of said openings may be used alternately by adjustment of the covers from one side to the other, but the two outer openings may be used at the same time to receive the loads from two wagons one on each side. In that

case the covers 21 would be raised by means of the chain 22 to a vertical position.

By providing for each opening two covers hinged at opposite sides of the opening, one to fold over the other, said covers being 70 operable either simultaneously or independently of each other, and both adapted to swing downwardly to close, and upwardly to open the openings, a great avoidance of danger is made possible. 75

A vehicle loaded with garbage may be brought to the edge of the hopper while the hopper is closed by both covers, as shown at the left in Fig. 2, and then the division cover 6 may be drawn into upright position 80 while the hopper is still closed, thus making a free open passage upward from the inner face of the division wall of the hopper up which passage the fumes and flame may be emitted when the supplemental cover 11 is 85 opened. The division cover 6 when thus raised to an upright position provides a shield or fender to prevent the blasts of air across the hopper which might fan a flame outward to the injury or inconvenience of 90 the vehicle, the team, or the attendant.

While I have shown and described one hopper having four openings as in Fig. 1, and another hopper having three openings, as in Fig. 4, it is within the scope of this 95 invention to change the number of openings as may be desired, and it is obvious that other changes in size, shape and arrangement of parts may be made without departing from the spirit of my invention. For 100 instance, the openings instead of being rectangular may be square, oval, round, or any other desired shape.

In Fig. 5 I have shown a hopper having two openings of the form shown in Fig. 4, 105 and in Fig. 6 I have shown a hopper having two openings of the construction shown in Fig. 1, a single opening instead of a plurality of openings being shown on each side of the division wall. 110

Referring to Figs. 1 and 2, for instance, a load of garbage may be hauled to the left-hand side of the hopper, the slides 16 moved outwardly to uncover the openings 2, the right-hand one of the covers 6 raised to a 115 vertical position, either of the covers 11 upon that side of the hopper opened, and a part of the load dumped; then the other cover 11 opened and another part of the load dumped; then both of the covers 6 may be 120 swung over to the left-hand side of the hopper, either one or both of the remaining covers 11 may be swung open and the balance of the garbage from the load at the left-hand side of the hopper may be dumped 125 upon the covers 6 and over said covers into the right-hand opening 2, thereby making it possible to dump the load into any desired one of the openings 2 from one side of the hopper. When it is desired to drive up to 130

the right-hand side of the hopper the slides 6 may be moved to the left-hand side. The inner or lower doors 11 or 20 as the case may be, close downwardly by gravity and come 5 to rest above the openings in the cap-plate so that in case either of the closures is fully down, the opening is positively closed against accidental reopening.

I claim:

1. A hopper provided with a division wall and a plurality of feed openings on opposite sides of said wall, closures for each of said openings, a plurality of covers hinged to said wall and each adapted to rest upon the 15 rim of the hopper and also adapted to fold upon the top of its companion cover.

2. In a hopper, the combination of a body portion provided with a division wall and formed with a plurality of feed-openings on 20 each side of said wall, a closure for each of said openings and a plurality of covers hinged to said wall, each cover extending the full length of said wall and adapted to be swung to either side thereof, and means for 25 holding said covers in any position to which they may be adjusted.

3. A hopper provided with a division wall and a feed-opening on each side of the division wall, two covers hinged to the division 30 wall side by side and adapted to swing upwardly to form an extension of the division wall and adapted to close said openings respectively and so that both of said covers may swing over either opening to form a 35 passage-way over that opening to the other opening.

4. A hopper provided with a division wall and having a feed-opening on each side of the wall, supplemental covers hinged to the 40 hopper at the outer sides of the openings and adapted to swing downwardly and close the openings; two division covers hinged to the division wall and adapted to swing outwardly over the supplemental covers and 45 rest upon the outer upper edges of the hopper and adapted to swing upwardly to form an extension of the division wall and adapted to swing both over the same opening to form a passage-way over that opening to the 50 other opening.

5. In a hopper, the combination of a body portion provided with a division wall and having a plurality of feed-openings on each side of said wall, two covers hinged to said 55 division wall, each cover extending the full length of the wall and adapted to be swung to either side thereof, and supplemental covers hinged to the hopper at the opposite sides of the openings from the division wall 60 and adapted to swing downwardly and close the openings, there being one supplemental cover for each opening.

6. In a hopper, the combination of a body portion provided with a division wall and 65 having a plurality of feed-openings on each

side of said wall, two covers hinged to said division wall, each cover extending the full length of the wall and adapted to be swung to either side thereof, supplemental covers hinged to the hopper at the opposite sides of 70 the openings from the division wall and adapted to swing downwardly and close the openings, there being one supplemental cover for each opening, and means for operating said supplemental covers simultaneously or independently.

7. In a hopper, the combination of a body portion provided with a division wall and having a plurality of feed-openings on each side of said wall, two covers hinged to said 80 division wall, each cover extending the full length of the wall and adapted to be swung to either side thereof, supplemental covers hinged to the hopper at the opposite sides of the openings from the division wall and 85 adapted to swing downwardly and close the openings, there being one supplemental cover for each opening, operating shafts mounted upon the operating shafts, spools upon the operating shafts, chains connecting the spools to the supplemental covers and clutches for 90 connecting the spools to the operating shaft, there being a clutch for each spool, so that the supplemental covers may be operated independently or simultaneously.

8. The combination with a crematory having a cap plate provided with feed openings, of a hopper, a division wall dividing the hopper into two parts, said hopper having a plurality of openings on each side of the 100 division wall registering with said feed openings, a slide between the cap-plate and the hopper for closing said openings, said hopper comprising an outer wall, a division wall dividing the hopper into two parts, division covers hinged to the division wall and adapted to cover the openings on one side to form a passage-way over said openings to the other openings or to cover the openings of both sides or to swing upwardly and form 105 an extension of the division wall; means for adjusting said covers to any desired position, supplemental covers hinged to the hopper at the outer sides of the openings, there being one supplemental cover for each opening, operating shafts mounted upon the frame of the hopper, spools upon the operating shafts, chains connecting the spools to the supplemental covers, and clutches connecting the spools to the shafts so that said 110 supplemental covers may be operated simultaneously or independently.

In testimony whereof, I have hereunto set my hand at Los Angeles California this 26th day of April 1906.

TIMOTHY CARROLL.

In presence of—

ANTON GLOETZNER, Jr.,
JULIA TOWNSEND.
